UNITED STATES PATENT OFFICE.

JAMES R. ELLIOTT, OF LONDON, CANADA.

DESIGN FOR A LUGGAGE-CARRIER.

SPECIFICATION forming part of Design No. 32,899, dated July 3, 1900.

Application filed June 1, 1900, Serial No. 18,782. Term of patent 7 years.

To all whom it may concern:

Be it known that I, JAMES R. ELLIOTT, a subject of the Queen of Great Britain, and a resident of London, Canada, have invented and produced a new and original Design for Luggage-Carriers, of which the following is a specification, reference being had to the accompanying drawings, forming part thereof.

Figure 1 is a perspective view of a luggage-carrier embodying my new design. Fig. 2 is a side elevation of the same.

As shown in the drawings, the leading or material features of my design consist of the curves or bends 1 and 2. The bend 2 is extended backward from the center vertical plane of the carrier, while the curves or bends 1 are forward from the vertical central plane. Above the bend 1 is another curve or bend, (in-

dicated by the numeral 3,) said bend being forward of the central vertical plane of the carrier. The bends 1 and 3 combined form substantially an S-shaped structure, while the bend 2 depends from the lower edge or end of this structure and is also substantially S-shaped. The structure is flattened in the bends 1 and 2, the remaining portion being substantially round in cross-section.

Having described my invention, what I claim as new, and desire to secure by Letters Patent, is—

The design for a luggage-carrier, as herein shown and described.

JAMES R. ELLIOTT.
